UNITED STATES PATENT OFFICE.

HARRY I. PHILLIPS, OF WATERBURY, CONNECTICUT, ASSIGNOR TO SCOVILL MANUFACTURING COMPANY, OF WATERBURY, CONNECTICUT, A CORPORATION OF CONNECTICUT.

CURTAIN FASTENER.

Application filed September 27, 1922. Serial No. 590,897.

To all whom it may concern:

Be it known that I, HARRY I. PHILLIPS, a citizen of the United States, residing at Waterbury, in the county of New Haven 5 and State of Connecticut, have invented a certain new and useful Improvement in Curtain Fasteners, of which the following is a full, clear, and exact description.

The object of this invention is to supply 10 a fastener for the curtains of automobiles and other vehicles and for use in other connections, wherein it is desirable to have a fastener reasonably secure against accidental release or unfastening and free from 15 rattling or chattering.

One type of such fasteners has a turn-button or head held in place by a spring and coacting ribs and grooves and it is to this type that my invention relates.

20 The present invention consists of novel features in the finger-piece of the turn-button or head itself and the connecting element by which the turn-button or head and the stationary base are united, as I will proceed 25 now to explain and finally claim.

In the accompanying drawings illustrating the invention, in the several figures of which like parts are similarly designated, Figure 1 is a side elevation and Fig. 2 30 is an end elevation showing in full lines the head in position of disuse and in dotted lines its position of use. Fig. 3 is a vertical section. Fig. 4 shows the parts of the fastener detached and in section excepting 35 that the spring is shown in elevation. Fig. 5 is a perspective view of the head and base connecting element, and Fig. 6 is a top plan view thereof. Fig. 7 is a top plan view of the base. Fig. 8 is an inverted plan view 40 of the finger-piece of the turn button or head closed over the connecting element.

The drawing is made on a larger scale than the commercial article.

The finger-piece 1 of the turn-button or 45 head is a shell of sheet or other metal, of any usual or approved form, preferably such as shown in the drawings, and having its bottom edge provided with lugs 2 and the intervening recesses 3. In the preferred 50 construction there will be four such recesses arranged in pairs in the major and minor axes of the shell.

The connecting element of the turn-button or head has a flange 4 provided with

55 lateral extensions 5 in its major and minor axes to fit the recesses 3 in the shell 1; and this flange is provided with the longitudinal and transverse ribs 6 and 7 respectively, extending from the center to the periphery. The flange is provided with a 60 depending tubular shank 8 which forms also the pivot for the turn-button or head.

When the flange 4 is fitted to the shell 1, the lugs 2 of the shell are closed down over it, as shown in Fig. 8 and thus these two 65 elements are rigidly secured against independent longitudinal movement, while the engagement of the extensions 5 on the flange with the recesses 3 in the shell 1 secure these two elements against independent rotary 70 movement. As will be understood, the engagement of the extensions with the recesses serves to mount the shell or finger-piece 1 upon the connecting member without the use of additional parts other than the closed- 75 in lugs.

It will be understood, therefore, that the finger-piece 1 and the shanked flange 4 constitute when assembled, the turnbutton or head.

80 The base 9 may be a sheet-metal shell or a casting, adapted to be attached to a body by any suitable means, such as the prongs 10. The face of the base is provided with longitudinal and transverse grooves 85 11 and 12 to receive the ribs on the flange, and said face is provided with a central hole 13 to receive the shank 8 of the connecting member when the connecting member and its attached finger-piece 1 are assembled. As shown in Fig. 3, this shank is located within the base and is connected therewith by means of the spring 14 over which the shank is headed, as at 15 to hold it in place. If desired or necessary, a washer 16 may be interposed between the spring 14 and the underside of the top of the base.

95 Of course, it will be understood that the spring is secured in place under tension, and its tendency is to draw the turn-button or head into intimate contact with the base, so that the complementary ribs on the turn-button or head member and the grooves in the base will cooperate to hold the turn-button or head in the position of disuse, as shown by the full lines in Figs. 1 and 2, as 100 well as in the position of use as indicated by the dotted lines in these figures. Not 105

only does the spring thus act, but it also serves to prevent rattling or chattering of the fastener.

5 Variations in the details of construction and the arrangement of parts are considered to be within the principle of the invention as set forth in the claims following.

10 While the invention is herein termed a curtain fastener, it is to be understood that it is not thereby intended to limit the application of the device.

15 While the construction shown is the preferred construction, still it is within the principle of the invention to use ribs on the base instead of on the turn-button or head and grooves on the turn-button or head instead of on the base.

What I claim is:—

20 1. In a curtain fastener, a turn-button or head adapted for use with and to turn upon a base and comprising a finger-piece provided with recesses, and a flanged connecting member constructed with lateral extensions to engage the recesses in the finger-piece, 25 said finger-piece provided with means for engaging the flanged connecting member to rigidly connect the two.

25 2. A turn-button or head for curtain fasteners, having a finger-piece provided with recesses, and a flanged connecting member constructed with lateral extensions to engage the recesses in the finger-piece, said finger-piece provided with means for engaging the flanged member to rigidly connect the two, and said flanged member having longitudinal and transverse ribs, said turn-button or head adapted for use with a complemental base.

30 3. A turn-button or head for curtain fasteners, having a finger-piece provided with recesses, and a flanged connecting member constructed with lateral extensions in its major and minor axes to engage said recesses, the finger-piece provided with lugs between its recesses for engaging the flanged member to rigidly connect the two, and said flanged member having longitudinal and transverse ribs which extend through the lateral extensions and are adapted to coop-

erate with a complemental base upon which the turn-button or head is mounted to turn and be held.

4. A curtain fastener, having a turn-button or head composed of a recessed finger-piece and a flanged connecting member constructed with lateral extensions to engage the recesses in the finger-piece, said finger-piece provided with means for engaging the flanged member to rigidly connect the two, and a base upon which the turn-button or head is pivotally mounted, the turn-button or head and the base having complemental cooperating means for holding the turn-button or head in given position on the base.

5. A curtain fastener, having a turn-button or head composed of a recessed finger-piece and a flanged connecting member constructed with lateral extensions to engage the recesses in the finger-piece, said finger-piece provided with means for engaging the flanged member to rigidly connect the two, the flanged connecting member having longitudinal and transverse ribs, and a base member upon which the flanged connecting member is pivotally secured, said base member having complemental longitudinal and transverse grooves for cooperation with the ribs of the flanged connecting member.

6. A curtain fastener, having a turn-button or head composed of a recessed finger-piece and a flanged connecting member constructed with lateral extensions to engage the recesses in the finger-piece, said finger-piece provided with means for engaging the flanged member to rigidly connect the two, the flanged member having longitudinal and transverse ribs, and a base member having complemental longitudinal and transverse grooves, and means for connecting the turn-button or head and the base member under tension.

In testimony whereof I have hereunto set my hand this 26th day of Sept., A. D. 1922.

HARRY I. PHILLIPS.
